(57) **CLAIM**

The ornamental design for a floating vessel, as shown and described.

DESCRIPTION

FIG. 1 is a top perspective view of a floating vessel showing the claimed design in accordance with a first embodiment, with environmental structure illustrated in broken lines;

FIG. 2 is a bottom perspective view thereof;

FIG. 3 is a left-side elevation view thereof, wherein a right-side elevation view thereof is a mirror image of the left-side elevation view;

FIG. 4 is a front elevation view thereof, wherein a rear elevation view thereof is a mirror image of the front elevation view;

FIG. 5 is a bottom plan view thereof; and,

FIG. 6 is a top plan view thereof.

Broken lines in the figures illustrate environmental structure and portions of the floating vessel that form no part of the claimed design.
